HEATING MEANS

Edwin L. Wiegand, Pittsburgh, Pa.

Application October 5, 1937, Serial No. 167,421

1 Claim. (Cl. 219--37)

My invention relates to heating means, more particularly to that type employing sheathed electrical heating elements, and an object of my invention is to provide improved supporting means for such heating elements, and improved heat reflecting and air circulation means for use in connection therewith.

In the drawing accompanying this specification, and forming part of this application, I have shown, for purposes of illustration, one form which my invention may assume, and in this drawing:

Figure 1 is a top plan view of an embodiment of the invention, parts of the same being broken away to expose the underlying construction,

Figure 2 is a vertical sectional view, corresponding substantially to the line 2--2 of Figure 1, while

Figure 3 is a bottom plan view of said embodiment, a portion thereof being broken away to better accommodate the view to the sheet.

The embodiment of the invention, as disclosed in the drawing, comprises heating elements 10 and 11, which may be in the form of annular, concentrically disposed heating units, each having a resistance member 12, enclosed within a metallic sheath, and suitably insulated therefrom, the particular construction of the heating elements per se, being well known. Each of the heating elements 10 and 11 is provided with terminals 13, to which are attached conductor bars 14, the outer ends of which extend into, and support, an insulating block 15, provided with apertures 16, through which energizing conductors (not shown) may be inserted into contact with terminals 17 of the conductor bars 14, this construction also being well known in the art.

The heating elements 10 and 11 are mounted concentrically upon a metallic support, preferably in the form of a substantially triangular, or heart-shaped cast spider 18, having curved ribs 19, diverging from an apex 20, toward, and connected to, outwardly inclined base sections 21--21, the latter having their ends 22--22 spaced apart, and connected by an inwardly curved connecting rib 23, the latter defining a space 24 through which the conductor bars 14 extend. At the apex 20, and base corners 25--25, the spider 18 is provided with outwardly extending projections 26, each of which extends through a suitably positioned aperture 27, in the skirt 28, forming part of a somewhat resilient adapter or supporting ring 29, which also is provided with an angular web 30, carrying an angular flange 31, adapted to rest upon the defining edge 32 of a stove aper-

ture. The supporting ring 29 is somewhat resilient, and because of the peculiarly spaced three-point connection thereof with the spider 18, application of some force between the points of connection, will enable the ring 29 to be conveniently sprung onto, or out of engagement with, the projections 26.

The spider 18 is also provided with a central arcuate rib section 33, the intermediate portion 34 of which, is connected by a pair of radially aligned cup members 35, with the apex portion 20 of the spider 18, the cup members 35 being offset to one side of the plane in which the ribs 19 lie, to provide a support upon which the heating elements 10 and 11 may rest, the end portions 36 of the rib 33 being connected to the base corners 25 by similar cup members 37 and 38, split rivets 39 being carried by the heating elements 10 and 11, extended through suitable apertures in the cup members 35, 37, and 38, and having their split ends 40 upset and lying within the cup members, thus securing the heating elements 10 and 11 to the spider 18. Connecting ribs 41 also connect the central rib section 33 with the ribs 19, and the ribs 41, as well as the ribs 19, and the ends 25 of the connecting rib 23, have lugs 42 thereon, projecting to the level of the heating element supporting surfaces of the cup members 35, 37, and 38.

The arcuate section 33 is also provided with inwardly extending, radially disposed arms 43, which support a small offset perforated platform 44, and at its opposite side the section 33, adjacent the ends thereof, is provided with a pair of spaced projections 45, adapted to extend through suitably spaced apertures 46 of a reflector 47, to insure proper positioning of the reflector. The reflector 47 is of dish-like form, inverted when in place, as best shown in Figure 2, cut out, as at 48, to clear the conductor bars 14, and having a central aperture 49, surrounded by a boss 50, the peripheral margin of the reflector 47 preferably having a downturned flange 51 extending therealong. With the reflector 47 disposed with its convex contour toward the under surface of the spider 18, the marginal portions thereof fall away from the spider 18, and leave a considerable space between the margins and the under surface of the spider 18, the central portion of the reflector resting against the arcuate section 33. The reflector 47 is held in centrally connected position by a wing nut 52 threaded upon a screw shank 53, extending through the aperture in the platform 44, and the screw shank 53 is carried by a cup-shaped disk 54 having a central protuber-

ance, the disk 54 preferably occupying almost the entire space within the heating element 11.

The relation of the heating elements 10, 11, spider 18, the reflector 47, and the disk 54, as described, results in very considerable air circulation beneath and about the heating elements 10 and 11, preventing overheating, especially when running idle, and permits substantial closing of the aperture of the heating element 11 by the disk 54, with increased heating efficiency. Also it will be apparent that the relation of the three-cornered spider 18, and of the supporting ring 23, is such that the ring 29 may conveniently be sprung onto and off of the spider 18, by slightly compressing the ring between the points of support.

It will be apparent to those skilled in the art that I have accomplished at least the principal object of my invention, and it also will be apparent to those skilled in the art that the embodiment herein described may be variously changed and modified, without departing from the spirit of the invention, and that the invention is capable of uses and has advantages not herein specifically

described; hence it will be appreciated that the herein disclosed embodiment is illustrative only, and that my invention is not limited thereto.

I claim:

An electric range unit, comprising: a heater and grating assembly including at least one electrical heating element of the resistance type and a grating constructed and arranged to support said heating element; a separate ring member for supporting said grating by engagement with radially outer portions of said grating; and a separate baffle member disposed below said grating, said baffle member having upper surfaces slanting downwardly to radially outer free marginal portions of said baffle member, said free marginal portions being below and spaced from the lower margin of said separate ring member so that air may enter in a generally radially inward direction between said free marginal portions and the lower margin of said separate ring member and proceed in a generally upward direction through said assembly into space above said assembly.

EDWIN L. WIEGAND.
